Primary Examiner—Mimosa De*(74) Attorney, Agent, or Firm*—Denton L. Anderson; Sheldon & Mak PC; Robert M. Hupe(57) **CLAIM**

The ornamental design for a rocking chair, as shown and described.

DESCRIPTION

FIG. 1 is a perspective view of the rocking chair of the invention;

FIG. 2 is a front view of the rocking chair illustrated in FIG. 1;

FIG. 3 is a side view of the rocking chair illustrated in FIG. 1;

FIG. 4 is a top view of the rocking chair illustrated in FIG. 1;

FIG. 5 is a bottom view of the rocking chair illustrated in FIG. 1;

FIG. 6 is a rear view of the rocking chair illustrated in FIG. 1; and,

FIG. 7 is a second perspective view of the rocking chair illustrated in FIG. 1, showing the underside of the rocking chair.

1 Claim, 4 Drawing Sheets
